SPRINKLER HOSE SUPPORT

Charles J. Gardner, Milwaukee, Wis.

Application January 29, 1959, Serial No. 54,388

Term of patent 14 years

(Cl. D91—1)

FIG. 1

FIG. 2

FIG. 3

FIG. 4

FIG. 5

Fig. 1 is a perspective view of the sprinkler hose support with portion of the supporting rod broken away for convenience of illustration only.

Fig. 2 is a side elevational view thereof.

Fig. 3 is a rear elevational view thereof as shown in Fig. 1.

Fig. 4 is a front elevational view thereof as shown in Fig. 1.

Fig. 5 is a top plan view thereof.

I claim:

The ornamental design for a sprinkler hose support, as shown.
